Primary Examiner — John Windmuller*Assistant Examiner* — John R Yeh(74) *Attorney, Agent, or Firm* — Walker & Jocke(57) **CLAIM**

The ornamental design for a night depository control panel, as shown and described.

DESCRIPTION

FIG. 1 is a front view showing our new design for a night depository control panel.

FIG. 2 is a front, left side perspective view thereof; and, FIG. 3 is a front, right side perspective view thereof.

The broken line disclosure in several views of the surrounding depository environment and the output from the display and other features of the night depository control panel is provided for illustrative purposes only and forms no part of the claimed design. The left, right and back sides of the night depository control panel are not visible during normal use, and only the design shown is claimed. The left, right and back sides of the night depository control panel are not ornamental and are not claimed.
